UNITED STATES PATENT OFFICE

**BERTRAM L. WATKIN, OF SYRACUSE, NEW YORK, ASSIGNOR TO PASS & SEYMOUR, INC.
OF SYRACUSE, NEW YORK, A CORPORATION OF NEW YORK**

DESIGN FOR A LIGHTING FIXTURE

Application filed June 29, 1931. Serial No. 40,355. Term of patent 3½ years.

To all whom it may concern:

Be it known that I, **BERTRAM L. WATKIN**, a citizen of the United States, and resident of Syracuse, county of Onondaga, State of New York, have invented a new, original and ornamental Design for a Lighting Fixture, of which the following is a specification, reference being had to the accompanying drawings forming a part thereof, and in which:

Figure 1 is a side elevation of a fixture showing the design of the present invention applied thereto;

Figure 2 is a bottom plan view thereof; and

Figure 3 is a fragmentary cross section view of a portion of the design and taken for instance on line 3—3 of Figure 1.

I claim:

The ornamental design for a lighting fixture as shown.
